DESIGN FOR AN OIL COOK STOVE

Walter E. Huenefeld, Cincinnati, Ohio

Application January 30, 1939, Serial No. 82,687

Term of patent 7 years

To all whom it may concern:

Be it known that I, Walter E. Huenefeld, a citizen of the United States of America and a resident of Cincinnati, in the county of Hamilton and State of Ohio, have invented a new, original, and ornamental Design for Oil Cook Stoves, of which the following is a specification, reference being made to the accompanying drawing, forming a part thereof.

The figure is a front perspective view of an oil cook stove, showing my new design.

The sides of the oil cook stove, not shown, are substantially plain.

The characteristic features of the design reside in the stove shown, having a front panel provided with flanged openings therein specifically as shown.

I claim:

The ornamental design for an oil cook stove, as shown and described.

WALTER E. HUENEFELD.
